TIE CLASP

Eugene Howell Martin, Akron, Ohio

Application July 31, 1933, Serial No. 683,076

1 Claim. (Cl. 24—49)

This invention appertains to new and useful improvements in the art of apparel, and more particularly to a novel made-up bow tie, which has as its principal object the provision of means whereby the tie can be readily clamped to the flap portion of the shirt collar in a convenient manner for use.

Another important object of the invention is to provide a bow tie capable of being handled and applied for use in a much more practical and convenient manner than present types of bow ties now on the market.

These and various other important objects and advantages of the invention will become apparent to the reader of the following specification.

In the drawings:—

Figure 1 represents a front elevational view of the tie in use.

Figure 2 represents a sectional view taken substantially on line 2—2 of Figure 1, looking downwardly.

Figure 3 represents a top plan view of the bow tie.

Figure 4 represents a rear elevational view of the tie.

Figure 5 represents a longitudinal sectional view taken substantially on line 5—5 of Figure 4.

Figure 6 represents a top plan view of the clasp.

Referring to the drawings wherein like numerals designate like parts, it can be seen, particularly in Figure 5, that the tie is made up of the front section 5 and the rear section 6. It is preferable that each section be of double ply construction and in order to form the two sections into a bow form, the central tie band 7 is employed and this, as shown in Figure 5, also circumscribes the clasp generally referred to by numeral 8. This clasp is attached to the tie in the manner shown in Figure 5 and its construction involves the use of an elongated strip of wire or similar

metal having an intermediate section *a* slightly curved. This wire is further formed into the clasp by being provided with inturned portions *b*—*b* which nearly meet at their opposed curved portions *c*—*c* where the wire again extends outwardly in substantial parallelism with respect to the portions *b*—*b* and terminates in loops *d*—*d* which tensionally bear against the outer ends of the portions *b*—*b*. The portions *b*—*b*, along with the intermediate portion *a* form leg portions *e*—*e* which are engaged and properly secured between the plies of the section 6, while the portions carrying the loops *d*—*d* extend outwardly and bear against the outside of the section 6. It will be observed that the band 7 assists materially in retaining this clasp to the tie form.

It can be seen now that by placing this clasp between the collar flaps and engaging the flaps between the back section 6 and the loops *d*—*d*, the loops in complement with the leg portions *e*—*e* snugly retain the tie in place.

Obviously, the tie can easily be removed by pulling the clasp loose from the collar flaps.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

A clasp of the character described comprising a strip of spring metal having its end portions bent inwardly to provide oppositely disposed legs and outwardly to provide tensioning members, the free ends of the outwardly disposed portions being rolled inwardly to provide substantially circular loops adapted to bear against the oppositely disposed leg portions.

EUGENE HOWELL MARTIN.
